UNITED STATES PATENT OFFICE.

MILLER B. HUDSON, OF CANANDAIGUA, NEW YORK, ASSIGNOR OF ONE-HALF TO OSCAR N. CRANE, OF SAME PLACE.

GATE-HINGE.

SPECIFICATION forming part of Letters Patent No. 251,885, dated January 3, 1882.

Application filed October 24, 1881. (No model.)

To all whom it may concern:

Be it known that I, MILLER B. HUDSON, of Canandaigua, Ontario county, New York, have invented a certain new and useful Improvement 5 in Gate-Hinges; and I do hereby declare that the following is a full, clear, and exact description of the same, reference being had to the accompanying drawings, in which—

Figure 1 is a front perspective view of the hinge with the roller removed from place. Fig. 2 is a rear perspective view of the securing-plates. Fig. 3 is a cross section of the hinge in line xx , Fig. 1. Fig. 4 is a perspective view of the roller-bearing and shaft.

15 My improvement relates to that class of hinges that are provided with a roller upon which the gate rolls back half-way and then swings around.

The invention consists in the particular construction and arrangement of the hinge, as hereinafter more fully described.

In the drawings, $A A$ represent two plates forming the case of the hinge, the same meeting at an apex and forming a right-angled frame fitting closely a corner of the square post B , to which it is secured by screws $a a$.

Crosswise in the center of the case is made a slot, b , extending into both plates, and made of such length as to allow the proper swing of the roller-shaft in either direction in turning the gate. At one end the slot is slightly enlarged, as shown at b' , to allow the shoulder of the roller-shaft to pass through. On the inner back side of the case are also cast two cross-bearings, $d d$, one above and the other below the cross-slot, as shown in the rear view, Fig. 2. These bearings rest in the angle and receive the ends of the roller-pintle between them and support the same, as will presently be described.

40 C is the roller-shaft, upon which rests the grooved roller D ; and E is the vertical pintle of the shaft, of the form shown in Fig. 4. The shaft has a small shoulder, g , against which the roller rests, and the roller is held by a pin, h , or other suitable means. The upper rail but one of the gate rests and runs upon the roller in the usual way. To connect the parts the shaft of the roller is first inserted through

the slot from the back side. The enlarged end 50 of the slot allows the shoulder to pass through; but when the shaft is turned away from the enlargement it cannot slide back. When fully inserted the ends of the pintle E rest between the cross-bearings $d d$ and cannot escape. 55 These bearings allow free turning motion, but prevent vertical movement, and they center the shaft in the slot, so that it does not touch the edges of the slot. The case is then screwed to the corner of the post, the corner having 60 been previously notched to receive the cross-bearings and pintle. The roller is then applied upon the outer end of the shaft, and the device is ready for use. Great simplicity and cheapness are attained, as the whole can be 65 made from cast-iron. By this means the roller is made close-fitting to the post, space only being left for the proper swinging movement of the roller.

I am aware that a bracket of V form has before been fitted to the corner of a post and provided with a roller to receive the gate; but in such case the bracket has an eye or socket, which stands outward, and the bearing which supports the roller has a short pin on its under side, which rests in the socket or eye, so that the whole bearing of the roller rests entirely outside of the bracket.

I am also aware that in other cases the bearing of the roller has been attached to the post 80 by staples, which allow it to swing in either direction. In my invention the case of the hinge fits closely to the corner of the post and has no projecting parts. The pintle of the roller-bearing rests entirely within the case 85 and in the notch in the post, and the shaft which supports the roller only projects outward. The construction of the case with the central cross-slot and with the bearings upon the back side between which the pintle rests 90 is specially adapted for the purpose.

Having thus described my invention, I claim—

1. The combination, in a gate-hinge, of the case consisting of the V -shaped plates $A A$, 95 fitting the corner of a post, provided with the cross-slot $b b'$, extending into both plates, and with the cross-bearings $d d$ on the back side

above and below the cross-slot, and the horizontal shaft C, supporting the roller, provided with the vertical pintle E, the shaft projecting out through the cross-slot and the pintle resting between the cross-bearings, as herein shown and described.

2. In a gate-hinge, the V-shaped case A A, provided with the cross-slot b b', extending into both plates, and the cross-bearings d d on

the back side above and below the cross-slot, to as and for the purpose specified.

In witness whereof I have hereunto signed my name in the presence of two subscribing witnesses.

MILLER B. HUDSON.
